(57) **CLAIM**

The ornamental design for a handle, as shown and described.

DESCRIPTION

FIG. 1 is a left, top, front perspective view of a handle embodying my new design;

FIG. 2 is a top plan view thereof;

FIG. 3 is a front elevational view thereof, the rear elevational view being identical to the front elevational view shown; FIG. 4 is a left side elevational view thereof, the right side elevational view being identical to the left side elevational view shown; and,

FIG. 5 is a bottom plan view thereof.

The broken line representations of an escutcheon base in FIGS. 1-4, and of mounting structure in FIG. 5, are for the purpose of illustration only, and form no part of the claimed design.
